RELATIVE HUMIDITY APPARATUS

Herman Knieriem, Midland, and Harold D. De Shon,
Bay City, Mich., assignors to The Dow Chemical Company,
Midland, Mich., a corporation of Delaware

Filed Dec. 3, 1965, Ser. No. 511,367

6 Claims. (Cl. 73—73)

This invention relates to apparatus for indicating the amount of water vapor present in dry cleaning solvent, and particularly to a humidity measuring meter for use with dry cleaning apparatus.

It has long been known that too much or too little water content in dry cleaning solvent could result in wrinkling, shrinkage, or redeposition (graying), on the fabric being cleaned.

The usual way to determine the amount of moisture present in the solvent involves removing a sample of the solvent from the cleaning apparatus and then analyzing to find the moisture content of the sample. Such tests are time consuming, made on a "spot" basis only, and often their accuracy is affected by the type and/or amount of the detergent present in the solvent and by the non-volatile matter present in the solvent.

Accordingly, a principal object of this invention is to provide an improved device for measuring the water moisture content in a dry cleaning solvent or the like.

Another object of this invention is to provide an improved, simple to install, easy to use device for continuously measuring the relative humidity of solvent in dry cleaning equipment.

In accordance with this invention, there is provided a cup-like housing having a transparent cover. A vapor input line extends into the central part of the housing, opening towards the back of the housing. A vapor output line is coupled through the housing wall remotely from the open end of the input line. A shield is disposed across the output opening in the housing to prevent the back splattering with solvent of a card disposed in the housing and having a plurality of patches thereon which change color in accordance with the moisture content of the vapor entering and leaving the housing.

Because the relative humidity of the solvent vapor is directly related to the amount of water in the solvent, the humidity gauge of this invention, when coupled between the solvent tank, for example, and a point on the dry cleaning apparatus where solvent is pumped over an upwardly extending bend in one of the solvent lines, continuously monitors the moisture (water) content of the solvent in the dry cleaning apparatus.

The invention, as well as additional objects and advantages thereof, will best be understood when the following detailed description is read in connection with the accompanying drawing in which:

FIG. 1 is a front elevational view, in section, of humidity measuring apparatus (with the gauge card removed) in accordance with this invention;

FIG. 2 is a sectional view taken along the line 2—2 of FIG. 1, and

FIG. 3 is a front elevational view of a humidity gauge card in accordance with this invention.

Referring to the drawing, and particularly to FIGS. 1 and 2, there is shown humidity measuring apparatus, indicated generally by the numeral 10, which includes a cylindrically shaped housing 12 having side walls, a closed end 13 and a removable closed end part 18 having a transparent face which is adapted to fit in a substantially gas tight manner over the side walls 15.

A vapor inlet tube 14 enters the housing 12 through the side wall 15 and has its open end 24 facing towards the end 13 of the housing.

2

A humidity indicating card holder 20 is disposed within the housing 12, held in place by means of welds 22 securing it to the inlet tube 14, so that it is positioned between the inlet tube and the transparent face of the end part 18.

The humidity indicating card 26, shown in FIG. 3, has tabs 28, 30 on it which fit into slots in the outwardly extending end parts of the holder 20.

A vapor outlet tube 16 extends through the wall 15 of the housing, the open end of the tube being covered by a shield or sleeve 24 which prevents accidental spraying of the card 26 in case solvent is inadvertently momentarily surged through the output line.

The humidity indicating card 26 is made of a blotter type paper having an area, the peripheral area 42, for example, of a fixed color.

A plurality of colored patches 32, 34, 36, 38, 40, for example, are provided on the card 26. The patches are composed of cobalt chloride in various concentrations whereby the patches change color as the relative humidity to which they are exposed increases. The relative humidity is read as being that designated for the colored patch which most nearly matches the fixed color in the peripheral area 42, for example. In one such card the patch 32 represented 30% relative humidity, the patch 34 represented 40% relative humidity, the patch 36 represented 50% relative humidity, the patch 38 represented 60% relative humidity, and the patch 40 represented 70% relative humidity when the respective patches matched the color of the peripheral area.

The patch 40, if pink in color, also represented over 80% relative humidity.

In operation, the input line 14 is coupled to the top of the solvent storage tank and the output line is coupled to the top of a loop in the solvent flow line (where a so called "vacuum breaker" element would be installed, for example). Thus, as solvent flows over the loop, a vacuum tends to be created, drawing vapor from the solvent tank through the input line 14, housing 12, and into the output line 16.

The vapor from the solvent tank contains water in an amount which is in equilibrium with the water in the solvent. Thus, the color of the patches on the card 26 in relation to the color of the peripheral area 42 is an indication of the relative moisture content in the solvent at the temperature condition existing in the vapor.

It has been found that the card 26 is not affected by the solvent vapor or the non-volatile materials in the solvent, but responds substantially only to the water moisture content of the vapor. There are, of course, no moving parts to become fouled or damaged. Further, the type and amount of detergent used in the solvent system do not affect the card 26.

Because this device provides a continuous means for monitoring the solvent relative humidity, the operator of the dry cleaning apparatus will know when to add or remove water from the solvent.

What is claimed is:

1. Relative humidity measuring apparatus comprising:
  - (A) an enclosed generally cylindrically shaped housing having an end wall, side wall, and a second end wall having a transparent face;
  - (B) a vapor inlet conduit, said vapor inlet conduit extending through said side walls and having an open end facing toward but spaced from said end wall;
  - (C) a vapor outlet conduit, said vapor outlet conduit extending through said side walls remote from said open end of said vapor inlet conduit;
  - (D) a backflow diverter element, said diverter element being disposed over said vapor outlet conduit within said housing;

- (E) a humidity indicator holding bracket fixedly disposed in said housing, and
  - (F) a humidity indicator including a card having a plurality of deposits thereon which each change color when exposed to specific amounts of humidity.
2. Apparatus in accordance with claim 1, wherein said deposits each contain cobalt chloride in a specified concentration.
3. Apparatus in accordance with claim 1, wherein said card is made of a blotter-like paper.
4. Apparatus in accordance with claim 1, wherein said card has tabs thereon which fit in said bracket.
5. Apparatus in accordance with claim 1, wherein housing is substantially gas tight.

5

10

6. Apparatus in accordance with claim 1, wherein said open end of said inlet conduit is near the longitudinal axis of said housing.
